(57) **CLAIM**

The ornamental design for a foldable headphone, as shown and described.

DESCRIPTION

FIG. 1 is a front perspective view of a foldable headphone, showing the first embodiment of my new design;

FIG. 2 is a rear perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a front perspective view thereof, in an alternate position;
FIG. 10 is a partial enlarged view of FIG. 1;
FIG. 11 is a partial enlarged view of FIG. 2;
FIG. 12 is a partial enlarged view of FIG. 3;
FIG. 13 is a partial enlarged view of FIG. 3;
FIG. 14 is a partial enlarged view of FIG. 8;
FIG. 15 is a front perspective view of a foldable headphone, showing the second embodiment of my new design;
FIG. 16 is a rear perspective view thereof;
FIG. 17 is a front elevation view thereof;
FIG. 18 is a rear elevation view thereof;
FIG. 19 is a left side elevation view thereof;
FIG. 20 is a right side elevation view thereof;
FIG. 21 is a top plan view thereof;
FIG. 22 is a bottom plan view thereof;
FIG. 23 is a front perspective view thereof, in an alternate position;
FIG. 24 is a partial enlarged view of FIG. 15;
FIG. 25 is a partial enlarged view of FIG. 16;
FIG. 26 is a partial enlarged view of FIG. 17;
FIG. 27 is a partial enlarged view of FIG. 17; and,
FIG. 28 is a partial enlarged view of FIG. 22.

The dashed broken lines in the figures depict portions of the foldable headphone and form no part of the claimed design. The dash-dot-dash broken lines are for notating enlarged views and form no part of the claimed design. The dot dash broken lines surrounding portions of the foldable headphones in FIGS. 1, 2, 3, 8, 15, 16, 17, and 22 and illustrated in the partial enlarged views of FIGS. 10, 11, 12, 13, 14, 24, 25, 26, 27, and 28, form no part of the claimed design.

The dot dash broken lines surrounding portions of the

foldable headphones in FIGS. 1, 2, 3, 8, 15, 16, 17, and 22

and illustrated in the partial enlarged views of FIGS. 10, 11,

12, 13, 14, 24, 25, 26, 27, and 28, form no part of the claimed

design.
